UNITED STATES PATENT OFFICE.

JAMES M. CONNER, OF NEW YORK, N. Y.

DESIGN FOR A FONT OF PRINTING-TYPE.

SPECIFICATION forming part of Design No. 14,389, dated November 6, 1883.

Application filed September 5, 1883. Term of patent 14 years.

To all whom it may concern:

Be it known that I, JAMES M. CONNER, of the city, county, and State of New York, have invented and produced a new and original Design for a Font of Printing-Type, of which the following is a specification.

The nature of my design is clearly shown in the accompanying typographic impression, to which reference is made; and it consists of an unshaded ornamented letter, the up and down portions of which are recessed at top and bottom, as shown, and the rounding portions of which are ornamented by the circular open spaces. The B, F, G, J, L, S, T, and Z are

further ornamented by the light curved line, 15 with heavy dot termination.

The character of the design is preserved in the symbols, numerals, and punctuation-marks, as shown.

Having now described my invention, I claim 20 as new—

The design for a font of printing-type, as shown and described.

JAMES M. CONNER.

In presence of—

WILLIAM V. H. HICKS,
A. SIDNEY DOANE.
